UNITED STATES PATENT OFFICE.

WILHELM H. WILHELMY, OF NEBRASKA CITY, NEBRASKA.

HYDROCARBON-BURNER.

No. 881,515.

Specification of Letters Patent. Patented March 10, 1908.

Application filed September 24, 1907. Serial No. 394,270.

To all whom it may concern:

Be it known that I, WILHELM H. WILHELMY, a citizen of the United States, residing at Nebraska City, in the county of Otoe and State of Nebraska, have invented certain new and useful Improvements in Hydrocarbon-Burners, of which the following is a specification.

My invention relates to improvements in hydrocarbon burners designed with special reference for use in connection with cooking and heating-stoves.

The primary object of the invention is to provide a generally-improved device of this class which will be exceedingly simple in construction, cheap of manufacture, efficient in use, and much better adapted to its intended purposes than any other device of the same class with which I am acquainted.

Another object is to provide a burner of this class which may be readily attached to or detached from any ordinary cooking-stove, the present embodiment being attached to a central bed-plate corresponding in its outline or contour to the central plate of an ordinary cooking-stove, the gas-generating-pipe or vaporizing portion being suspended within the fire-box and directly beneath the stove-top or plates, while the oil or vapor-catching base-pan is mounted near the bottom of the fire-box and is provided with a flame-spreader-head disposed directly beneath the burner-tip and mixer-opening whereby to produce a maximum amount of heat, where most desired, with a minimum consumption of fuel. By regulating the drafts, by means of the ordinary damper attachments of the stove, the proper amount of air is admitted to the mixer to mingle with the vapor at the point of combustion, thereby creating an intense clear white heat and reducing the formation of soot and dirt to a minimum.

With these and other ends in view, the invention consists in the novel construction, arrangement and combination of parts, hereinafter described, illustrated in the accompanying drawings, and particularly pointed out in the appended claims.

Referring to the drawings, forming a part of this specification, Figure I, is a side elevation of the improved burner. Fig. II, a top plan of the same, a portion of the attached central bed or supporting-plate being broken away for the purpose of clearer illustration of the parts. Fig. III, a central longitudinal sec-

tional view, taken through the attached supporting-plate and oil-burning-pan, one half of the vaporizing yoke-pipe being removed.

Similar characters of reference designate like parts throughout all the figures of the drawings.

The improved burner, in the present instance, is mounted upon a supporting-plate 1, corresponding in its outer contour or outline to the form of the central bed-plate of an ordinary cooking-stove. The plate 1, is provided with openings through which the vertical portions of the oil-feeding inlet-pipe 2, and vapor outlet-pipe 3, pass, said oil inlet-pipe being secured in position by means of an elbow-pipe 4, below and a nut 5, above said plate. The plate 1, is also provided with a mixer-opening 6, provided with a depending annular flange 7. The elbow-pipe 4, of said oil inlet-pipe 2, and the lower end of said vapor outlet-pipe 3, communicate or intersect with a horizontally-arranged elliptical gas-generating or vaporizing yoke-pipe 8, by means of cross and T-pipe fittings 9, and 10, respectively, said yoke-pipe being, preferably, made up of two U-shaped branches or laterally-extending wings 8^a, having their inner or meeting ends threaded and taking into the ends of said pipe-fittings. The upper end of the oil inlet-pipe 2, is connected to a second or horizontal oil inlet-pipe 11, by means of an elbow-pipe 12, said oil inlet-pipe 11, terminating in a needle-valve-body 13, provided at its upper end with a screw-cap or bonnet 14, and spindle 15. The valve-body 13, is provided with a depending portion 16, threaded on its exterior for connection with an oil receiving pipe or hollow wire (not shown) communicating with any suitable and convenient source of supply.

The upper end of the vapor outlet-pipe 3, is connected to a downwardly-curved pipe or elbow 17, by means of an elbow-pipe 18, said downwardly-curved pipe or elbow 17, carrying on its lower portion a depending nozzle or burner-tip 19, superposed directly over the mixer-opening 6. A base-pan 20, is carried and supported beneath the mixer-opening 6, of the supporting-plate 1, by means of a solid vertical supporting stem 21, said stem 21, being provided with a nut or head 22, and screw-threaded at its lower end and taking into a threaded opening in the base-pan, the upper end being threaded in an elbow-pipe 23, secured in one of the

arms of the cross-pipe-fitting 9. The pan 20, is provided with a truncated cone-shaped flame-spreader-head or block 24, secured thereto by means of a cap-screw 25, and 5 mounted directly beneath the mixer-opening 6, and burner-tip 19, above, whereby to deflect or spread the burning vapor or gas, as it impinges thereon, over and above the pan 20, and against the upwardly and out- 10 wardly-extending flange or rim 25, of the latter.

The operation of the device is as follows: First, open needle-valve allowing oil to pass through the inlet and outlet-pipes until a 15 little oil has been allowed to escape through the depending nozzle-tip 19, through the mixer-opening 6, upon and over spreader-head 24, and base-pan 20; then close valve, light oil and when generating-yoke-pipe 8, 20 becomes hot enough, gas will escape from nozzle 19, down through mixer-opening 6, and will ignite above the base-pan depending within the fire-box of the stove; then open valve again and regulate the flow of 25 oil for the required amount of heat desired. By regulating draft-dampers on stove, the proper amount of gas and air are mixed in passing through mixer-opening 6. As the burning-vapor or gas strikes the flame- 30 spreader-head or block 24, it is deflected or spread out as hereinbefore described, thus insuring a complete vaporization of the oil. Furthermore, by reason of the construction set forth provision is made for perfect com- 35 bustion for the carbon contained in the vapor fed to the flame; and the maximum degree of the heat units is developed and utilized to the best advantage with a minimum consumption of oil.

40 Having thus described my invention, without having attempted to set forth all the forms in which it may be made, or all the modes of its use, I declare that what I claim and desire to secure by Letters Patent, is,—

45 1. A burner, comprising a supporting-

plate provided with a downwardly-extending flanged mixer-opening, an inlet-pipe and an outlet-pipe intersecting said supporting-plate said outlet-pipe terminating in a depending burner-tip immediately above said 50 mixer-opening, a horizontally - arranged elliptical vaporizing yoke-pipe mounted immediately beneath said supporting-plate and intersected and carried by said inlet and outlet-pipes by means of cross and T-pipe 55 fittings, respectively, and a flanged base-pan carried beneath said mixer-opening by means of a vertical stem secured to said cross-pipe fitting.

2. In a burner, an elliptical vaporizing 60 yoke-pipe comprising two U-shaped branches having their ends threaded and taking into cross and T-pipe fittings, oil inlet and vapor outlet pipes communicating with said yoke-pipe through said cross and 65 T-pipe fittings, respectively, and a peripherally-flanged base-pan suspended beneath said yoke-pipe by means of a vertical stem secured to said cross-pipe fitting.

3. In a burner, the combination with a 70 supporting-plate carrying a vaporizing yoke-pipe made up of two branches and a mixer-opening provided with a depending flange, a cross and T-pipe fitting uniting said two branches of the yoke-pipe, and an oil inlet 75 and vapor outlet pipe secured to said cross and T-pipe fittings, respectively; of a peripherally-flanged base-pan suspended beneath said supporting-plate and yoke-pipe by means of a vertical stem secured to said 80 cross-pipe fitting, and a flame-spreader-head carried by said base-pan and mounted directly beneath said mixer-opening.

In testimony whereof I have affixed my signature, in presence of two witnesses.

WILHELM H. WILHELMY.
